UNITED STATES PATENT OFFICE.

OWEN H. MORRIS, OF NEW HAVEN, CONNECTICUT.

HORSE-COLLAR FASTENING.

SPECIFICATION forming part of Letters Patent No. 279,177, dated June 12, 1883.

Application filed March 6, 1883. (Model.)

To all whom it may concern:

Be it known that I, OWEN H. MORRIS, a citizen of the United States, residing at New Haven, in the county of New Haven and State 5 of Connecticut, have invented a new and useful Fastening for Horse-Collars, of which the following is a specification, reference being had to the accompanying drawings.

This invention relates to horse-collar fastenings, and has for its object to provide a simple, inexpensive, durable, and efficient means for fastening the two parts of the collar, that will possess superior efficiency in the performance of its function.

15 In the drawings, Figure 1 is a face view of my improved fastening. Fig. 2 is a similar view, with one of the plates removed to show the interior arrangement. Fig. 3 is a vertical transverse sectional view illustrating the operation of the catch in dotted lines. Fig. 4 is a perspective detail view of the catch.

Referring to the drawings, A designates a casing that is adapted to inclose the catch, and B is a plate having a hook-shaped extension, 25 C, which is received into the casing, and is engaged by the catch in the latter to secure the two parts of the fastening together. The casing A is to be secured in any suitable manner on one end of the collar, and the hook-plate 30 B is to be likewise secured to the other end of the collar, so that these two parts of the fastening come together when the ends of the collar are pressed into contact with each other. The casing A is provided with a recess, D, in

35 its edge, to receive the hook C, and from this recess extends a slot, E, down through the casing, this slot being beveled on one side to form a shoulder, F, near the bottom, and a small slot, G, in the side of the casing is formed 40 above this shoulder F. The casing is preferably formed by a main plate or piece, H, in which is formed the recess and the main slot, and an outside plate, I, that is secured against the plate H, and is formed with the shoulder

45 F and slot G. In the slot E is arranged a catch plate or bar, J, that projects from the bottom of the casing, and is provided with a lateral pin, K, that works in the slot G, to limit the movement of the plate in the slot E. A 50 flat spring, L, is secured at its top end to one side of the bar J, and projects from the same.

This spring is provided with a shoulder, M, that, when the bar is pushed up in the slot E to engage the hook C when the latter enters the recess in the casing, automatically engages 55 the shoulder F, so that the said bar J will not slip down from engagement with the hook C. When it is desired to release the said hook, so that the parts of the fastening will be disconnected, the lower end of the spring has only 60 to be pressed against the plate or bar J at its lower projecting end, when the shoulder M will be disengaged from the shoulder F, and the said bar can be drawn down from engagement with the hook C. 65

I claim as my invention—

1. The combination, with the casing having a recess which is adapted to receive the hook of an engaging-plate, and provided with a slot extending from the said recess and opening at 70 the edge of the casing, of a latch-bar sliding in the said slot and provided with a flat spring projecting from its side to retain it in position, and a hooked plate arranged to be received in the recessed casing, as set forth. 75

2. The combination, with the casing having a recess and a slot extending from the said recess and provided with a shoulder near its terminus, of a latch-bar sliding in the said slot and projecting from the casing, said bar being 80 provided with a spring projecting from its side and having a shoulder that is arranged to engage the shoulder in the slot, and a hooked plate arranged to be received in the recessed casing, as set forth. 85

3. The combination of the casing secured to one section of the horse-collar, having the recess, the slot extending therefrom and provided with a shoulder, and a slot in its side above the said shoulder, the latch-bar having the lateral pin and provided with a shouldered spring projecting from its side, and the hook-plate secured to the other section of horse-collar, as set forth. 90

In testimony that I claim the foregoing as 95 my own I have hereto affixed my signature in presence of two witnesses.

OWEN H. MORRIS.

Witnesses:

HENRY C. GOODWIN,
JOHN TUTTLE.
